Inventor

Fritz Will,

By

Geo. P. Kimmel, Attorney

Patented Oct. 31, 1922.

UNITED STATES PATENT OFFICE.

FRITZ WILL, OF ALTON, ILLINOIS.

FOUNTAIN MOP.

Application filed February 24, 1921. Serial No. 447,500.

To all whom it may concern:

Be it known that I, FRITZ WILL, a citizen of the United States, residing at Alton, in the county of Madison and State of Illinois, have invented certain new and useful Improvements in a Fountain Mop, of which the following is a specification.

This invention relates to improvements in fountain brushes or mops, and has for one of its objects to improve the construction and increase the efficiency and utility of devices of this character.

Another object of this invention is to provide a device of this character constructed of independently connected mop fabrics, and independently attached to a tubular conductor which is likewise the handle of the mop or brush, the parts of the brush being separable so that impaired parts may be removed without discarding the remainder of the brush or the handle.

With these and other objects in view the invention consists in certain novel features of construction as hereinafter described and claimed and then specifically pointed out in the claim, and in the drawings illustrative of the preferred embodiment of the invention:—

Figure 1 is a view illustrating one means of employing the improved device.

Figure 2 is an enlarged section view.

Figure 3 is a transverse section on the line 3—3 of Figure 2.

The improved device comprises a tubular conductor 10, through which the cleansing liquid is adapted to be passed, the member 10 preferably being a section of hose, and coupled to a source of supply 11, connected by a coupling 12, thereto.

The mop portion comprises an outer mop fabric 13 folded intermediate its length and arranged around the conductor at one end and secured in place by a suitable band 14, the band 13 being passed around the mop structure near its fold as shown in Figure 2.

By this means the outer mop fabric is securely supported in position upon the exterior of the conductor at its discharge end.

The improved device likewise includes an inner mop fabric 15 formed of a plurality of portions each folded intermediate its length and having its folded portion inserted into the discharge end of the conductor as shown in Figure 2. A wire 16 is passed through the folded portion of each of the inner mop fabric members and the projecting portions

twisted externally of the inner mop member and the ends of the twisted portion separated and passed in spaced relation through the sides of the conductor and secured at the outer sides of the same, preferably by twisting as shown at 17.

By this simple means, the double mop structure is secured in place and attached firmly to the conductor, while at the same time the mop structure may be readily removed for renewal or repair, as will be obvious.

The outer mop portion extends to a sufficient extent above the discharge end of the handle 10 to engage over the twisted outer ends 17 of the holding wires of the inner mop portions, to effectually prevent the escape of water from the handle at these points.

The mop fabric may be of any required size and of any suitable material, and will be found very convenient for use for various purposes, for instance, in washing and cleaning automobiles as illustrated in Figure 1. The flow of water through the tubular members 10 and 11 passes through the mop fabric and enables the surface over which the brush is moved to be thoroughly cleansed, as will be obvious.

The preferred embodiment of the invention is disclosed in the drawings and set forth in the specifications, but it will be understood that any modifications within the scope of the claims may be made in the construction without departing from the principle of the invention or sacrificing any of its advantages.

Having thus described the invention, what is claimed as new is:—

1. In a device of the class described, a tubular conductor provided with transverse openings adjacent one end, a plurality of inner mop fabrics folded intermediate their length and having their folded portions disposed within the tubular conductor, and a wire loop extending through the folds of each of the inner mop fabrics and entwisted beyond the loops with the free ends of each loop extended through the perforations of the conductor and anchored externally of the same.

2. In a device of the class described, a tubular conductor provided with transverse openings adjacent one end, a plurality of inner mop fabrics folded intermediate their lengths and having their folded portions disposed within the tubular conductor, a

wire loop extending through the folds of each of the inner mop fabrics and entwisted beyond the loops with the free ends of each loop extended through the perforations of the conductor and anchored externally of the same, an outer mop fabric folded intermediate its length and disposed around the ex-

terior of the conductor and over the anchor portions of the loops, and a binder member securing the outer mop fabric to the conductor.

In testimony whereof, I affix my signature hereto.

FRITZ WILL.
